UNITED STATES PATENT OFFICE

JOHN H. DEAN, OF BIRMINGHAM, ALABAMA, ASSIGNEE, BY DIRECT AND PURCHASE ASSIGNMENTS, TO THE U. S. SULET & NEPAL CULVERT CO., A CORPORATION OF DELAWARE.

SHEET-METAL CULVERT.

1,040,817.

Specification of Letters Patent.

Patented Jan. 7, 1913.

Application filed April 30, 1912. Serial No. 894,271.

To all whom it may concern:

Be it known that I, JOHN H. DEAN, a citizen of the United States, residing at Birmingham, in the county of Jefferson and State of Alabama, have invented certain new and useful Improvements in Sheet-Metal Culverts, of which the following is a specification, reference being had thereto to the accompanying drawing.

10 This invention relates to sheet metal culverts to be used as drains, aqueducts, or the like, and more particularly to such culverts of the sectional and nestable type, wherein the same are built of sections adapted to be knocked down and like sections nested together in shipment and storage, and also wherein the sections may be readily and easily set up and formed into a complete culvert at the place where the same is to be used.

It is the purpose and object of this invention to generally improve the construction of such culverts, and to provide a culvert which will be comparatively simple in construction, cheaply made, strong and durable and also well suited for the purpose for which it is intended. These objects are attained by making the culvert of one or more flat bottom sections and one or more curved or curved top sections, which top and bottom sections are so constructed as to be securely fastened together along their longitudinal edges for retaining the sections in connected relation.

15 A further object of the invention is to provide a culvert which is made up of corrugated metal sections, of the construction herein referred to, said sections having rigid metal strips or bars preferably welded to the same at or near their longitudinal edges, so that when the sections are assembled, the strips of opposite sections lie adjacent one another and serve as a means to which metal clips or other fastening devices may be applied for holding and retaining the sections in connected and assembled relation. In connection with this object of the invention, it may be here noted that the rigid metal strips or bars are connected directly to the convex corrugations of the culvert sections, in which event they serve to materially strengthen the sections and also provide passages between the sections and said strips for the insertion of the fastening clips just referred to.

The invention furthermore has for its object the provision of metal fastening clips which are rigidly secured to the metal strips or bars of the flat bottom sections, and said being preferably welded thereto when the sections are being made and prior to the assembling of the top and bottom sections.

Further objects and advantages will appear in the following description, it being understood that various changes in form, proportions and minor details of construction may be resorted to within the scope of the appended claims.

I have illustrated my invention in the accompanying drawings, in which:

Figure 1 is a side elevation, partly in section, of a culvert showing the sections of the same constructed in accordance with the invention, and in connection therewith, a plan view of the same, and a detail view, transverse, showing the strips of metal, taken on the line B—B of Fig. 1.

Referring to the drawings, the same show a bottom section 1 of the culvert, which is formed of corrugated sheet metal, it being desired to be understood that this section 1 may be constructed with a plurality of longitudinal strips or bars, upon the upper and lower edges of said bottom section 1, secured as shown, the longitudinal edges thereof, are arranged, so that metal strips or bars 2, are preferentially rigid strips, and in the preferred embodiment of the invention these strips are welded only to the convex corrugations of said bottom section. It is to be here noted that metal strips or bars may be fastened to the sections in any other suitable manner, such as by rivets, bolts or other fastening means, but welding is preferred, in which event the metal sections themselves do not have to be punched with holes or any part of the metal of said sections cut away to receive the bolts, rivets or other fastening means, which necessarily invites rust and corrosion and materially disturbs the vital parts of the metal sections.

The top section 3 is indicated at 3 and is preferably arched or curved as clearly shown in Fig. 3 of the drawings. These arched sections are also transversely corrugated and provided along their longitudinal edges, with metal strips or bars 4, similar to those secured to the bottom section. The strips or bars 4, as is true of the strips or bars 2, referred to, are secured only to the convex corrugations of the arched sections, and it is

to be noted that in so attaching the strips, passage-ways 5 are provided between the sections and said metal strips for receiving metal clips 6 for fastening adjacent strips of top and bottom sections together. It is to be further noted that the longitudinal edges of the arched sections 3 are so cut or shaped as to conform to the curvature of the upper surface of the corrugated bottom sections, as indicated at 7, thereby permitting said longitudinal edges to contact with the bottom sections for their entire length and also neatly fit the concave and convex corrugations thereof when the sections are in assembled relation.

In the preferred embodiment of my invention the strips or bars as indicated at 2 and 4, are continuous strips running substantially the entire length of each section, it being noted, however, that they stop short of at least one corrugation on one end of each section to permit the overlapping of the meeting ends of longitudinally adjacent sections. These strips, however, may be made of short sections arranged at intervals along the longitudinal edges of the culvert sections, as will be obvious, and as more clearly set forth in an application for patent filed by me on April 22, 1912, Serial No. 692,326.

In assembling the sections of this culvert, the longitudinal edges of the top or arched sections are adapted to rest upon the bottom sections at points intermediate the metal strips 2 which are arranged along each longitudinal edge of said bottom sections. In this assembled position the metal strips 4 secured to the arched sections assume a position substantially at right angles to the strips 2, and furthermore lie adjacent thereto, so that said adjacent strips may be easily fastened together for retaining the sections in their assembled relation.

It is of course to be understood that any form of metal clip may be used for fastening the adjacent strips of opposite sections together, although it is preferred to use the form of fastening means shown in the drawings, wherein the clips 6 are made of sheet metal and welded to the underside of the strips or bars of the bottom sections at points intermediate the convex corrugations of said sections. These clips are welded to the strips 2 as just referred to, during the course of manufacture of these sections, and of course prior to the assembling of the sections at the place where the culvert is to be used. It will be readily understood that these clips fastened to the strips at the points indicated and opposite the concave corrugations of the bottom sections, may lie flat and within said concave corrugations while being shipped or in storage. At the time the top and bottom sections are to be assembled, however, these clips 6 are bent up into a vertical position to receive the top sections, said clips being

adapted to pass through the passage-ways formed between the top sections and the metal strips or bars and then bent over said metal strips to fasten adjacent strips 2 and 4 together for the purpose specified herein.

Many advantages are obtained by a construction of sheet metal culvert along the lines as herein specified, some of which advantages have already been set forth in the objects of this invention, and it will be perfectly obvious that the assembling of the parts is simple and effectual and is of such a character that it may be accomplished where the work of installing a culvert is being carried on. It is to be further noted that the sections are constructed without outstanding flanges and that the top or arched-shaped section is adapted to be connected to the bottom section with its longitudinal edges abutting the upper face of said bottom section, and that both the top and bottom sections may be fastened together without the use of bolts, rivets, or similar fastening devices engaging the metal sections themselves.

Having thus described my invention, what I claim and desire to secure by Letters Patent is:—

1. A sheet metal culvert comprising a flat bottom section transversely corrugated, a top section bent into arched form and having its longitudinal edges so cut as to conform to the curvature of the upper surface of the bottom section, metal strips or bars secured along the longitudinal edges of each section, and means for fastening the strips of top and bottom sections together.

2. A sheet metal culvert section provided with transverse corrugations, a metal strip or bar secured to the convex corrugations of said section along the longitudinal edge thereof, and a metal clip welded to the under side of said strip at a point intermediate the convex corrugations.

3. A sheet metal culvert comprising a flat bottom section, a top section bent into arched form and having its longitudinal edges abutting the upper surface of said bottom section, metal strips or bars secured along the longitudinal edges of each section, and means for fastening the strips of top and bottom sections together.

4. A sheet metal culvert comprising a flat bottom section, a metal strip or bar secured along each longitudinal edge thereof, a top section bent into arched form and having its longitudinal edges abutting the upper surface of said bottom section at points intermediate the metal strips of said bottom section, a metal strip or bar secured along the longitudinal edges of said top sections, and means for fastening adjacent strips of both sections together.

5. A sheet metal culvert comprising a flat bottom section, a metal strip or bar secured along each longitudinal edge thereof, a top

section having longitudinal edges abutting the upper surface of said bottom section, a metal strip or bar secured along the longitudinal edges of said top section, the strips of opposite sections arranged adjacent one another on each side of the culvert and at right angles, and means for fastening adjacent strips together.

6. A sheet metal culvert section provided with a metal strip or bar secured to said section along its longitudinal edge, and fastening means rigidly and permanently secured to said metal strip, and adapted for engagement with a complementary section.

7. A sheet metal culvert section provided with a metal strip or bar secured to said section along its longitudinal edge, and a metal clip rigidly secured to said metal strip.

8. A sheet metal culvert section provided with transverse corrugations, a metal strip or bar secured to the convex corrugations of said section along the longitudinal edge thereof, and fastening means rigidly and permanently secured to said metal strip, and adapted for engagement with the strip of a complementary section.

9. A sheet metal culvert section provided

with transverse corrugations, a metal strip or bar secured to the convex corrugations of said section along the longitudinal edge thereof, and a sheet metal clip rigidly secured to the metal strip at points intermediate said convex corrugations.

10. A sheet metal culvert section provided with a metal strip or bar secured along its longitudinal edge, and fastening means welded to said strip at points intermediate its ends.

11. A sheet metal culvert comprising complementary sections, and fastening means rigidly and permanently secured to one of the sections and adapted to be detachably connected to the other section for firmly retaining the sections in connected relation.

12. A sheet metal culvert comprising complementary sections, and a metal clip welded to one of the sections and adapted to be bent into engagement with the other section for fastening the sections together.

In testimony whereof I have affixed my signature in presence of two witnesses.

JOHN H. DEAN.
